(57) **CLAIM**

The ornamental design for a tape dispenser, as shown and described.

DESCRIPTION

FIG. 1 is a perspective view of a tape dispenser showing the new design;

FIG. 2 is a side view, the opposite side being a mirror image thereof;

FIG. 3 is a top view thereof;

FIG. 4 is a bottom view thereof;

FIG. 5 is a front view thereof;

FIG. 6 is a rear view thereof; and,

FIG. 7 is an alternate view of FIG. 1 showing the front and side views as transparent for the purpose of clearly depicting the dispensing mechanism and inner contours of the tape dispenser. This view is not an additional embodiment.

The broken lines depicting certain structural features of the tape dispenser are for illustration purposes only and form no part of the claimed design.
